UNITED STATES PATENT OFFICE.

ELMER A. SPERRY, OF CLEVELAND, OHIO, ASSIGNOR, BY MESNE ASSIGNMENTS, TO MORGAN ELECTRIC MACHINE COMPANY OF WEST VIRGINIA, OF CHICAGO, ILLINOIS, A CORPORATION OF WEST VIRGINIA.

RACK-RAIL FOR LOCOMOTIVES.

SPECIFICATION forming part of Letters Patent No. 772,680, dated October 18, 1904.

Application filed December 8, 1902. Serial No. 134,254. (No model.)

To all whom it may concern:

Be it known that I, ELMER A. SPERRY, a citizen of the United States, residing at Cleveland, in the county of Cuyahoga and State of Ohio, 5 have invented a certain new and useful Improvement in Rack-Rails for Locomotives, of which the following is a specification.

My invention relates to rack-rails which are adapted at the same time to be employed 10 as an electrical conductor for supplying the passing cars or trains with electrical energy.

My invention consists of certain details in structure, insulation, support, and construction by means of which such rail is rendered 15 practical and successful, so that it may be manufactured at a reduced cost and properly withstand the strain and hard usage of the service to which it is subjected.

A device for carrying out my invention in 20 one of its forms is shown in the accompanying drawings, forming a part hereof.

In Figure 1 is a transverse section of a simple form of rack-rail carrying its insulating-sheath. Fig. 2 is a side elevation showing one 25 means of cross-tying the insulating-sheaths with a perforated binder. Fig. 3 is a longitudinal section of one of the rail-joints, showing at the same time a fish-plate as insulating-support. Fig. 4 is a plan view of the fish- 30 plate, showing means for clamping the insulator. Figs. 5 and 6 show a detail of the insulating-sheath at or near an insulator. Fig. 7 shows a transverse section of a rack where the unperforated portions at the sides are 35 turned down, giving the rail a U-shaped section, showing also means for insulating and for securing the insulating-sheath. Fig. 8 is a side elevation of same, showing further detail of an anchor-plate. Fig. 9 is an elevation 40 of a rail-joint connector. Fig. 10 is a section of a rail-joint inserted within the rail, showing the tapering sides and method of holding. Figs. 11 and 12 are sections at different points in the length of the rail bond 45 or connector shown in Fig. 9. Fig. 13 is a view from beneath, showing the fish-plate and insulator-clamp with the insulator in sec-

tion. Fig. 14 is a top view of a rail with standard-width opening. Fig. 15 is similar to Fig. 14, except wider openings. Fig. 16 50 is a section of a rail-joint with plain fish-plate. Fig. 17 is an end section of a rack-rail.

Similar letters of reference indicate like parts throughout the several views.

It has been found that where the rack-rail 55 used for traction purposes is at the same time employed as an electrical conductor for supplying the locomotive, cars, &c., certain features must be presented in the structure so organized that the rail may perform both of 60 these important functions without allowing the restriction introduced by one to interfere with the rigidity required by the other. At the same time it must be free and clear from any connection with the earth. This fact I 65 utilize to likewise free the teeth, which in this event may be constituted of the bridges or webs between the adjacent perforations in a flat rail or a rail of other contour or section, the requisite being that the perforated rail shall 70 have other unperforated sections upon which it can depend for electrical conductivity. For the use of such a rail rectangular perforations are preferable, though they may be of any desired form and are found to be practicable 75 so long as they are able to free themselves beneath by providing spaces in which accumulations may fall or be forced by the advance driving sprocket or gear. While upon the one hand the rail must be solidly anchored, 80 usually against strains which are not only longitudinal but lateral as well, yet the supporting function must be carried out through an insulating medium, and the rail must also be provided with a sheath or shield to prevent 85 accidental contact therewith. The sheath must be so arranged as not to interfere with the normal operation of the driving device of the locomotive which is adapted to coöperate therewith.

To satisfy all these conditions in a single structure, simple means have been found for the construction of the sheath which renders the rail practically inaccessible from the fact

that nothing but wood or insulating material is presented by the finished rail, a narrow slot in the middle of the upper face of the rail being the only means of access to the charged rail, the slot being sufficiently deep to prevent accidental contact. This insulation A is preferably secured to the lateral edges of the unperforated section, which flanks the line of perforations of the rail B, preferably by being clamped to the rail, and therefore supported by the rail, the opposite insulating-sheaths being secured one to the other through the rail, as illustrated in Fig. 7, or one above and the other under the rail, as illustrated in Figs. 1 and 2. The narrow slot B' permits access of driving connection to rack.

To secure the necessary continuity of the rack for electrical purposes, and especially where the rack is made up of the usual sections, fish-plates C may be provided at the joints, which are made to impinge upon each adjacent end B² of the rack-rails, the parts being brought into metallic contact, thus insuring adequate conductivity at the joint. These combined fish-plates and conductors may at the same time be utilized as points of support and insulation for the rail, and in Figs. 3, 4, and 13 and also Figs. 5 and 6 such an arrangement is illustrated, wherein an insulator D, preferably a petticoat-insulator, is suitably supported from the road-bed, being shown in Fig. 3 as having its supports D' spiked to a sleeper or tie D². The insulator is supplied with the usual groove D³ or equivalent holding means for the supported structure, into which is clamped a device for supporting the rail. In the case shown in Figs. 3, 4, and 13 this device at the same time constitutes in part or whole a portion of the fish-plate. One of the clamping parts D⁴ is shown as being integral with the fish-plate and has its concave dependent portion perforated to register with the perforations of the rail and also affording a loop for the hook D⁵. The other clamping member, D⁶, is secured to the other by a bolt D⁷ and at the same time fastened to the fish-plate, preferably by slotted holes D⁸, so as not to interfere with the clamping action upon the insulator, the slots being so located as to receive the bolts which normally serve to secure rigid contact between the fish-plate and the rail. The structure shown in Figs. 7 to 12 has the advantage of providing extensive unperforated portions B², flanking the line of perforations on either side, which do not extend the lateral width of the rack as a whole, inasmuch as they turn downwardly at a point near the sides of the perforations instead of protruding laterally, as in Fig. 1. While the outside line of this U-shaped or channel section may be rectangular, its inside line provides a tapering of the sides. This bevel is useful as affording means for securing the most intimate contact between the rail and the fish-plate or connector E, (seen in Fig. 10,) 60

where the fish-plate or connector is wedged up in between the tapering sides and suitably held, a slight upward pressure affording a comparatively powerful clamping action. The enlarged section below the rail may be utilized for increasing conductivity of the fish-plate or connector, especially at the center. The fish-plate thus tapers from the center to each end. (See Fig. 9.) This fish-plate or connector is cut away at E', as shown. 75

I have found that the wearing qualities of my perforated rack-rail for railways is greatly improved by employing hard metals; but the difficulty in working these metals has led me to harden the faces of the perforations, and this I find can be done by swaging or compressing the metal either by a blow or heavy pressure at or near the face of the perforation. This may be done even during the process of punching by a further advance of the punch 80 or by the simple device of grinding the die, so as in effect to produce a "dull" side. I find the metal is not only compressed adjacent to the perforations on the dull side or sides, but the upper corner by this simple device 90 may be pulled down and rounded, affording a very much more natural contact for the rolling action of the gear-teeth which coöperate with these faces.

The hardening of the rack-rail at the adjacent edges of the perforations is illustrated at F F in Fig. 3, where the upper corner is shown pulled down and rounded (shown at H H, Fig. 3) and where the swaging action or extra pressure is applied at the top, the density thus varying from the top downwardly, as clearly indicated in the shading F F adjacent to the holes in this figure. Here it will be seen that a web portion is located directly above the insulator, and the freeing of the perforations 100 on either side may take place through the cup-shaped web, which is also perforated at I I to partially register. 105

The sheath located on one side of the lateral face of the rack is connected and held to the sheath on the opposite side of the lateral face of the rack in any convenient manner—as, for instance, with an insulating-binder F⁹ (see Fig. 2) and which binder is preferably pierced or perforated directly under the perforations of the rack. 110

I have illustrated in detail a particular construction embodying my invention; but it is of course evident that this construction may be greatly varied and that some of the parts 115 may be omitted and others used with parts not here shown without departing from the spirit of my invention.

By means of this invention the operation of electric-railway systems, particularly in 120 such places as mines and tunnels, and especially where grades exist, is very greatly simplified and made much cheaper and more efficient and satisfactory and permits the adaptation to circumstances and conditions not 125 130

commercially possible in the ordinary electric-railway system. The arrangement of the rack, consisting of special rack devices, the insulation and installation of the rack with regard to the track, all aid in an efficient and reliable roadway which may be operated under economical conditions and which insures efficient action, wholly absent in the ordinary railway systems.

10 I claim—

1. The combination with a conducting rack-rail for electrically-operated cars of an insulating and protecting cover therefor and provided with an opening or slot for the part that engages the rack, said conducting rack-rail forming a support for said insulating and protecting cover.

15 2. A perforated rack-rail, insulated supports for such rail and an insulating-sheath supported by the rail.

20 3. A rack-rail serving as an electrical conductor, the rail consisting of a bar, perforations along the center of the bar flanked on either side by unperforated portions, insulating-supports for such rail located at intervals and insulating-sheaths for the unperforated portions of the rail, protruding above and supported by the rail.

25 4. A perforated rack-rail, insulating-supports for such rail, and an insulating-sheath supported by the rail, both the sheath and the rail being clear from the ground or surface along which the track is laid.

30 5. A perforated rack-rail, insulating-supports for such rail, an insulating-sheath supported by the rail and an open space under the center of the rail.

35 6. A rack-rail serving as an electrical conductor, the rail consisting of a bar, equidistant perforations along the center of the bar flanked on either side by unperforated portions, insulating-supports for such rail located at intervals and insulating-sheaths for the unperforated portions of the rail protruding above and supported by the rail, said sheath protruding below as well as rising above the rail.

40 7. A rack-rail serving as an electrical conductor, the rail consisting of a bar with equidistant perforations along the center of the bar flanked on either side by unperforated portions, insulating-supports for such rail located at intervals and insulating-sheaths for the unperforated portions at the two lateral edges of the rail and supported by the rail, and binders for connecting the sheath of one edge with that of the other.

45 8. A rack-rail serving as an electrical conductor, the rail consisting of a bar with equidistant perforations along the center of the bar flanked on either side by unperforated portions, insulating-supports for such rail located at intervals and insulating-sheaths for the unperforated portions at the two lateral edges of the rail and supported by the rail,

and binders of insulating material for connecting the sheath of one edge with that of the other.

9. A rack-rail serving as an electrical conductor, the rail consisting of a bar with equidistant perforations along the center of the bar flanked on either side by unperforated portions, insulating-supports for such rail located at intervals and insulating-sheaths for the unperforated portions at the two lateral edges of the rail and supported by the rail, and perforated binders of insulating material for connecting the sheath of one edge with that of the other.

10 10. A perforated rack-rail, insulating-supports for such rail, an insulating-sheath supported by the rail, the sheath fitted with longitudinally-disposed strips protruding below the rail.

15 11. A perforated rack-rail, insulating-supports for such rail, an insulating-sheath supported by the rail, the insulating-sheaths being located upon the edges of the rail, cross-bindings for connecting the two sheaths, and longitudinal portions of the sheaths lying under the rail between the binders.

12. A perforated rack-rail, insulating-supports for such rail, the perforations being rectangular, equidistant, and centrally disposed with reference to the rail and practically flush with the under surface of the rail, the upper edges of the perforations being rounded.

17 13. A perforated rack-rail, insulating-supports for such rail, the perforations being rectangular, equidistant, and centrally disposed with reference to the rail and practically flush with the under surface of the rail, the upper corners of the edges of the perforations which lie transverse to the length of the rail being rounded.

14. A perforated metallic rack-rail, insulating-supports for such rail, the perforations being rectangular, equidistant, and centrally disposed with reference to the rail, the metal abutting the faces of the perforations which lie transverse to the length of the rail being compressed.

15 15. A perforated metallic rack-rail, insulating-supports for such rail, the perforations being rectangular, equidistant, and centrally disposed with reference to the rail, the metal abutting the faces which lie transverse to the length of the rail being hardened.

16. A perforated metallic rack-rail, insulating-supports for such rail, the perforations being rectangular, equidistant and centrally disposed with reference to the rail, the metal abutting the faces of the perforations which lie transverse to the length of the rail being compressed from the top of the rail downwardly.

17. In a perforated rack-rail for an electric railway where the rack is used as a conductor, insulating devices for the rack consisting of an insulator, metallic support between the in-

sulator and the rail, the perforations within the support registering with perforations within the rail.

18. In a perforated rack-rail for an electric railway where the rack is used as a conductor, insulating devices for the rack consisting of an insulator, metallic support between the insulator and the rail, the perforations within the support registering with perforations within the rail, and a clamp for the insulator constituting a part of the support.

19. In a perforated rack-rail for an electric railway where the rack is used as a conductor, insulating devices for the rack consisting of an insulator, and a metallic support between the insulator and the rail, the perforations within the support registering with perforations within the rail, and fastenings for the rail.

20. In a perforated rack-rail for an electric railway where the rack is used as a conductor, insulating devices for the rack consisting of an insulator, metallic support between the insulator and the rail, the perforations within

the support registering with perforations within the rail, and a fish-plate for the rail forming part of the support.

21. In a perforated rack-rail for an electric railway where the rack is used as a conductor, insulating devices for the rack consisting of an insulator, metallic support between the insulator and the rail, the perforations within the support registering with perforations within the rail, a clamp for the insulator constituting a part of the support, a lock-joint for the clamp and slots in the clamp for receiving bolts from the rail.

22. In a rack-rail for an electric railway where the rack is used as a conductor, insulating devices for the rack consisting of a fish-plate, a convex projection on the plate for clamping an insulator, perforations in the rail registering with perforations in the fish-plate and a perforation in the convex projection.
